UNITED STATES PATENT OFFICE.

SIMEON H. ASHTON, OF RHINELANDER, WISCONSIN.

DESIGN FOR A SPOON.

43,812.

Specification for Design.

Patented Apr. 8, 1913.

Application filed December 11, 1911. Serial No. 665,157. Term of patent 3½ years.

To all whom it may concern:

Be it known that I, SIMEON H. ASHTON, a citizen of the United States, residing at Rhinelander, in the county of Oneida and State of Wisconsin, have invented a new, original, and ornamental Design for Spoons, of which the following is a specification, reference being had to the accompanying drawing, forming part thereof, in which—

Figure 1 is a plan view of a spoon show-

ing my new design. Fig. 2 is a cross section of the bowl of the spoon.

I claim:

The ornamental design for a spoon as shown.

SIMEON H. ASHTON.

Witnesses:

RUTH DANFIELD,
K. R. BEYGEH.

Copies of this patent may be obtained for five cents each, by addressing the "Commissioner of Patents, Washington, D. C."

It is hereby certified that in Letters Patent No. 43,812, granted April 8, 1913, upon the application of Simeon H. Ashton, of Rhinelander, Wisconsin, for a "Design for a Spoon," errors appear requiring correction as follows: On the drawing, signature of inventor, for "Simson H. Ashton" read *Simeon H. Ashton*; in the specification, name of second-mentioned witness to signature of inventor, for "K. R. Beygeh" read *R. P. Beygeh*; and that the said Letters Patent should be read with these corrections therein that the same may conform to the record of the case in the Patent Office.

Signed and sealed this 20th day of May, A. D., 1913.
